TILT-TURN TOY

George S. Brackett, Jr., Waynesboro, Pa.

Application March 29, 1945, Serial No. 585,495

6 Claims. (Cl. 46—213)

1

My invention relates to a wheeled toy, and it is an object of the same to provide a toy that can be steered with accuracy and satisfaction through the operation of manual propelling means.

A further object of the invention is to provide means for attachment of any one of a plurality of propelling means in different positions, each of which propelling means will serve as a steering means when located on the toy in the manner intended.

Another object is to provide a toy that can steer itself by merely being tilted when in use.

Another object is to provide a self-steering toy with simple means to limit the tilting movement of the body or chassis whereby the steering is effected.

Another object is to provide a toy vehicle such as herein described with means to permit the rear axle to remain in normal position with its wheels on the floor, even though its body be tilted laterally for steering the vehicle.

Another object is to provide a wheeled toy that can move freely over uneven ground or over low obstacles, without jolting or upsetting, due to the freedom of movement of the axles.

Another object is to provide improved means for connecting a trailer to a wheeled toy vehicle.

Another object is to provide a toy of the character described herein, which toy shall be of very simple and inexpensive construction, yet not flimsy, and in which the chassis may consist of solid wood or metal, or may be in one or two unitary sheet-metal members.

Referring now to the drawings, which are made a part of this application and in which similar reference characters indicate similar parts:

Fig. 1 is a plan of one form of the invention, Fig. 2, a side elevation of the same,

Fig. 3, a section on line 3—3 of Fig. 2,

Fig. 4, a section on line 4—4 of Fig. 2,

Fig. 5, a side elevation of a modified form, partly in section,

Fig. 6, a top plan of the rear portion of the toy vehicle shown in Fig. 5,

Fig. 7, a section on line 7—7 of Fig. 5, and

Fig. 8, an elevation of a control handle.

In the drawings, reference character 10 indicates the chassis or body of a toy vehicle having front wheels 11, 11 and rear wheels 12, 12. The front wheels are mounted for free rotation on an axle 13, which in turn is mounted for oscillatory movement about an inclined pivot 14, which is inclined at preferably about 35° to the vertical. The axle 13 is located, with reference to the body of the toy, in a downwardly facing V-shaped

notch in the bottom of said body, which is here indicated as being a solid body of wood or other suitable or convenient material, though a hollow body of sheet-metal, either in one piece or in several rigidly united parts, may be substituted. The front face of the notch provides a steering face 15 at an angle of about 55° to the vertical by reason of its cam action on the axle that rests against it and is so held by the pivot pin 14, whereas the rear face 16 acts as a stop to limit the oscillation of the axle in either sense about its pivot 14.

The rear wheels 12, 12 are mounted at opposite ends of an axle 17 for free rotation thereon, said axle being mounted on a horizontal pivot 18 so that the body 10 can be tilted without raising the wheels off the floor or other supporting surface. The axle is located, with reference to the body 10, in a transverse notch in said body, and the upper flat face of said notch serves as a stop to limit the tilting of the body with respect to the axle and its wheels.

The propulsion and steering of the vehicle may be effected in any one of several ways, and for this purpose I have shown two loops or staples 20, 21, at the top of the body, one at the forward end and the other directly above the center of mass, to either one of which there may be attached a cord or string or the like 22 with a ball 23 or other suitable handle or grip at its end for convenience in grasping the same. Attachment of such a cord to the loop 21 is usually deemed preferable, since that places the point of attachment directly over the center of mass 35 of the toy, which is of advantage in that the vehicle may be lifted off the floor and when replaced it will at once stand on all four wheels again, and it will also keep its balance better while being moved about and in being tilted for steering purposes. It will be obvious that a mere tilting of the chassis to one side or the other by pulling the cord will cause the steering surface 15 to cam the axle 13 in one sense or the other, and so will cause the front wheels to 40 change their relation to the vehicle body, the one moving backward and the other forward with relation thereto, thus steering the vehicle to one side or the other of its path, the direction and amount of veering depending on the direction of pull and on its amount and the resulting tilt of the chassis.

The tilting of the chassis is limited by the engagement of the axle with the rear face 16 of the notch, said face forming a stop for the axle 50 in either direction of tilt of the chassis and thus

limiting the amount of possible change of direction and preventing upsets. The tilting of the chassis at the rear end of the vehicle in either direction is limited by engagement of the rear axle 17 with the upper face of the notch at the rear of the vehicle, at 19.

A simulation of a steering wheel is provided at 24, but this feature has no function aside from improvement in appearance of the toy and increase in resemblance to a motor vehicle.

An inclined socket is provided at 25 for insertion of a steering handle or post (Fig. 8) comprising a lower member 26 to which is pivoted an extension 27 with a ball or other grip thereon at its upper end, which handle may serve for propulsion and steering of the vehicle when placed in the socket 25. It will be understood that only one steering and propulsion member will ordinarily be provided on the vehicle at a time, but all three may be permitted to remain in place if desired.

In that form of the invention shown in Figs. 5 to 7 the body 30 is provided with means at 31 and 32 for attachment of a cord 33 that may carry a grip 34. A front axle 35 with wheels 36 at its ends is mounted on an inclined pivot 37 passing through the steering surface 38 at the front of the inverted V-shaped notch in the lower part of the body and the rear wall of the notch at 39 provides a stop surface for the axle. All of these parts are, or may be, as in the form of the invention first described.

The body 30 terminates short of the rear axle 40, which is mounted in a rear axle assembly block 41 and which carries wheels 42 and 43 mounted to rotate on the axle 40, this axle preferably fitting tight in the hole provided therefor in the block 41. The block is fixed to the body 30 by means of a pin 45 located about midway between two shoulders 46, 47, on the block, which shoulders serve as stops permitting the body 30 to swing about the pin 45 but limiting its movement to either side. The block has an overhang at its rear to protect and conceal the headed end of pin 45. Forwardly of the overhang the block is provided with a socket 49 to receive a pin or hook or the like for connecting a trailer to the vehicle in convenient manner.

It will be obvious to those skilled in the art that many changes may be made in my device, all without departing from the spirit of the invention, and therefore I do not limit myself to what is shown in the drawings and described in the specification, but only as indicated in the appended claims. For example, the block 41 might have integral projections to carry the wheels instead of a separate rear axle 40.

Having thus fully described my invention, what I claim is:

1. A wheeled vehicle having a two-piece chassis, comprising front and rear chassis members, a front axle on which the front chassis member is laterally tiltable, connections whereby the vehicle is steered when the front chassis member is tilted, and means connecting the rear chassis member to the front member so as to permit the front member to tilt without tilting the rear member.
2. A device as in claim 1, said means comprising a horizontal pivot pin.
3. A device as in claim 1, said rear chassis member having stops thereon to limit tilting movement of the front chassis member.
4. A device as in claim 1, said rear chassis member having an upwardly-opening socket for connection to a trailer or the like.
5. In a wheeled toy vehicle, a one-piece chassis with downwardly facing notches in its under face, axles in said notches, said axles being pivoted to the chassis to permit the chassis to tilt with reference to the axles, means actuated by the tilting of the chassis for turning the front axis to steer the vehicle, a string attached to the body above the front axle to propel the vehicle and also to tilt the chassis and thereby to steer the vehicle, the forward notch being V-shaped, and an inclined pivot holding the front axle in contact with the forward face of the notch, the rear face of the said notch limiting the relative tilting of the chassis with respect to the front axle.
6. In a wheeled toy vehicle, a chassis, front and rear axles on the chassis, a downwardly opening V-shaped notch at the under side of the chassis, an inclined pivot projecting from said face and supporting the front axle in contact with the forward face of said notch, means connecting the rear axle tiltably to the chassis, and a string connected to the chassis above the front axle for propelling the vehicle and for tilting the chassis to one side or the other relatively to its axles, whereby the connection between the chassis and the front axle causes the said axle to turn and thus to steer the vehicle.

GEORGE S. BRACKETT, JR.
